UNITED STATES PATENT OFFICE.

CHARLES M. PEABODY, OF SOUTH ORANGE, NEW JERSEY, ASSIGNOR TO THE KNY-SCHEERER COMPANY, A CORPORATION OF NEW YORK.

WAVE-MODIFIER FOR X-RAY SYSTEMS.

1,129,424.

Specification of Letters Patent. Patented Feb. 23, 1915.

Application filed October 2, 1913. Serial No. 792,935.

To all whom it may concern:
Be it known that I, CHARLES M. PEABODY, a citizen of the United States, and a resident of South Orange, New Jersey, (whose post office address is care of Kny-Scheerer Company, No. 404 West Twenty-seventh street, in the borough of Manhattan, county, city, and State of New York,) have invented certain new and useful Improvements in Wave-Modifiers for X-Ray Systems, set forth in the following specification.

This invention relates to commutating machines for X-ray systems, which machines are usually employed for rectifying 15 an alternating current into a pulsating current.

In machines of the type mentioned, according to the relative circumferential extent of the commutating parts, a definite 20 extent of each of the various electromotive force or current waves is made available in the working circuit. It is usual to employ the crest portion of these waves symmetrical on opposite sides of the apex of the wave 25 crest. Present day activities in X-ray work have become such that wave portions of a predetermined extent relative to the entire wave as well as of a predetermined angular position in the wave cycle are best adapted 30 to some particular use. For instance, some X-ray tubes may work at the highest efficiency when excited by a wave portion comprising a very considerable extent of the wave above the zero line whereas other tubes 35 cannot be operated with any degree of efficiency unless the excitation is limited to the apices of the wave crests.

The object of the present invention is to provide for the modifying of the wave portions employed in an X-ray system so that, 40 by selective variation, those portions desired for the work in hand may be made available, and so that the undesired wave portions may be discarded.

With this end in view there is contemplated within the invention the employment 45 of at least a pair of coöperating commutating parts, which, of course, may be multiplied in pairs to the necessary number according to the type of commutating machine. One of these parts is a conducting finger and the other of these parts is a conducting arc preferably formed from a strip of metal bent into the form of an arc. One

of the parts revolves about a fixed axis, and 55 the other of the parts is relatively fixed against revolution, both normally lying substantially in the normal plane of revolution of the revolving part; and means for varying the circumferential extent of said conducting arc which portion coöperates with 60 said conducting finger to cause a flow of current from one to the other, all for the purpose of selectively varying the number of degrees or the angle of rotation through 65 which the said two parts coöperate to complete the working circuit.

Especially on account of the high potentials employed in X-ray work considerable difficulty is experienced even in commutating 70 an alternating current into a pulsating current. To provide in such a commutator means for selectively varying the extent of the current wave made serviceable presents a serious engineering problem. The space 75 available for any purpose in a commutating machine is not only mechanically limited, but much of that space mechanically permissible is unavailable on account of the high electric potentials present. It has been 80 found that the best results are obtainable by employing conducting arcs which are relatively fixed against revolution, but at least a portion of which is rotatable out of the plane of revolution of the conducting 85 finger. By making the conducting arc in sections with only a central section rotatable upon a radial pivot, a wide range of selective adjustment may be effected without causing unpermissible cross discharges to 90 the movable section of the contacting arc. In connection with such an arrangement the rotatable central section of the conducting arc may be adjusted into its various positions merely by attaching a cord of insulating 95 material to one of its ends.

The above will be pointed out more particularly in the following claims which should be read in connection with the following specification which is descriptive of 100 an illustrated embodiment of the invention shown in the accompanying drawings, in which like characters designate corresponding parts, which form a part of this application, and in which—

Figure 1 is a perspective view of a rectifier embodying this invention; Fig. 2 is a detailed view of the means for modifying

the extent of available wave portion; Fig. 3 is a side view of the part shown in Fig. 2 and also showing diagrammatically a regulating cord; and Fig. 4 is a diagram illustrating the wave portions referred to in this application.

To the end that the type of machine to which this invention is applicable may be better understood reference may be had to 10 the patent to Blum, No. 1,003,325, and the patent to Snook, No. 954,056, both of which describe rectifiers and rectifying systems. In Fig. 1 is illustrated an apparatus fundamentally similar to that shown diagrammatically in Fig. 6 of the patent to Blum, reference to which has been made.

1 is a containing cabinet for conveniently housing and mounting the various parts; 2 is a suitable switchboard for the electric 20 control; 3 is a source of alternating current and of mechanical power for the revolving commutating parts C. This source 3 is illustrated as a synchronous generator. The revolving parts C are driven through 25 the medium of the shaft 4 coupled to the source of power 3 through the medium of a suitable coupling 5. T indicates any suitable form of high potential power transformer and is supplied with alternating 30 current from the source of power 3 through the leads 6 and 7 feeding the primary winding of the transformer T. The secondary terminals of the transformer T are indicated by 8 and 9.

35 Fixed to the shaft 4 are a plurality of diametrically parallel spider arms 10 and 11. Angularly positioned at 90° relatively to the arms 10 and 11 are a plurality of diametrically parallel spider arms 12 and 40 13 which are likewise fixed to the shaft 4. The arms 11 and 12 occupy substantially the same plane at right angles to the shaft 4. Fixed to the ends of these arms are conducting fingers 14, 15, 16, 17, 18, 19, 20, 45 and 21, mounted to revolve in circular paths about the fixed axis of the shaft 4. These conducting fingers are electrically connected in pairs, 14 and 15 by the rod 22; 16 and 17 by the rod 23; 18 and 19 by the rod 50 24; and 20 and 21 by the rod 25.

Coöperating conductively for the working circuit with the revolving conducting fingers 14, et cetera, are the conducting arcs 26, 27, 28, 29, 30, and 31 relatively fixed 55 against revolution.

For the purposes of this application each conducting finger 14, et cetera, and one of the conducting arcs such as 26 lying in the plane of revolution of the finger are together termed a pair of coöperating commutating parts, one of which, in the embodiment illustrated, a conducting finger such as 14, being adapted to revolve about the fixed axis of the shaft 4 and the other, 60 in the illustrative embodiment the arc 26,

being relatively fixed against revolution and lying in the normal plane of revolution of the other part 14. It is of course to be understood that this language likewise inclusively describes a structure in which the 70 conducting fingers 14 et cetera are the relatively fixed parts and the conducting arcs 26 et cetera are the revolving parts attached to the ends of the spider arms 10, 11, 12, and 13. In either case the conducting arc should be normally concentric with the path of revolution of the revolving part, the common center being the axis of the shaft 4.

In the embodiment illustrated the secondary terminals 8 and 9 of the transformer T are connected to the conducting arcs 29 and 28 respectively by the leads 40 and 41. It is therefore obvious that the connections of the revolving and rotating commutating parts C are such that the conducting arcs 26 and 27 will constitute the terminals for one working circuit and the conducting arcs 30 and 31 terminals for another and separate working circuit. It is of course understood that suitable leads and binding posts if desired are to be provided to connect with these arcs 26, 27, 30 and 31. Furthermore, it is to be understood that this invention is by no means limited to the precise number of commutating parts illustrated and described because any multiplication thereof may be effected to accomplish any of the well known ends in the art, as for instance, those described in the patent to Blum previously referred to.

The present invention has to do with the means for varying the extent of the angle of rotation throughout which the coöperating commutating parts actually coöperate to close a secondary circuit. This means is 105 illustrated in detail in Figs. 2 and 3 for the conducting arc 28. The conducting arc 28 is preferably formed out of a suitable curved strip of metal which is severed short of its ends by the diagonal cuts 42 and 43 110 into three sections 44, 45, and 46. The end sections 44 and 46 are fixed to suitable insulating members such as 47 and 48. The main central section 45 is pivoted as by the bolt or rivet 49 to the insulating support 47 and is shown fitted with a spiral spring 50 located about the bolt 49 and tending to rotate the central section 45 in a counter-clock-wise direction when viewed in the position of Fig. 3. The inclined cuts 42 and 43 cause the end pieces 44 and 46 to serve as stops to limit this counter-clock-wise rotation of the center part 45 so that when the three parts 44, 45, and 46 are in normal position the central part 125 presses firmly against the end parts to complete the entire conducting arc 28, or where the end parts are omitted the cord 53 may serve as a stop. One end of the central part 45 has suitable means such as the 130

wall of the perforation 52 for attaching a flexible non-conducting cord 53. This cord 53 passes diagonally upward and to the right over a suitable guide 54 thence 5 along the top wall of the cabinet through the exit bushing 54 to an adjusting means 55. In like manner a cord 56 is attached to a similar central portion for the conducting arc 29 which is of symmetrical construction to the arc 28. This cord 56 passes over its guide 57, likewise through the bushing 54, and to its attachment with the adjusting member 55. A series of scaled sockets 58 for the reception of the plug 55 10 may be provided on the exterior of the cabinet 1 so that by drawing the cords out to accommodate the seating of the plug 55 in the lower perforations 58, the arcs 45 will tilt out of the plane of rotation of 15 the coöperating conducting fingers 15 and 17, to reduce the effective circumferential extent of the coöperating conducting portions.

When the conducting arcs 28 and 29 exist 25 as is shown in Figs. 2 and 3 it may be conceived that the wave formation available is the form of wave portion delivered to either the terminals 26 and 27 or the terminals 30 and 31 and would be α of Fig. 4. Immediately upon the rotation of the central portions 45 into the position shown in dotted lines in Fig. 3, the wave portion delivered by the said terminals would become limited as shown for example by the wave portion 30 γ . The more the central portion 45 is tilted toward right angles to its normal position the less is the circumferential extent thereof coöperative in the plane of revolution for the other commutating part. When 35 exact right angular position is reached practically only the apex of the wave crest is available in the working circuit as may be illustrated by the wave portion β in Fig. 4.

In the preferred form the adjustable conducting arcs may be limited to the conducting arcs directly connected with the terminals of the secondary transformer T although it is of course to be understood that 45 these adjustable conducting arcs might take 50 the position of the arcs 30 and 31 and the arcs 26 and 27 without changing the spirit of the invention.

What is claimed and what is desired to be secured by United States Letters Patent is:

55 1. A commutator, for X-ray systems comprising a pair of coöperating commutating parts, one being adapted to revolve about a fixed axis and the other being relatively fixed against revolution substantially in the 60 normal plane of revolution of the other part, one of said parts being a conducting finger and the other of said parts being a conducting arc normally concentric with said fixed axis; and means for varying the 65 circumferential extent of said conducting

arc which coöperates with said conducting finger for the purpose of selectively modifying the commutated wave, said means comprising a radial pivot about which at least a portion of said arc may be swung out 70 of said normal plane of revolution.

2. A commutator, for X-ray systems comprising a pair of coöperating commutating parts, one being adapted to revolve about a fixed axis and the other being relatively 75 fixed against revolution substantially in the normal plane of revolution of the other part, one of said parts being a conducting finger and the other of said parts being a conducting arc normally concentric with 80 said fixed axis; and means for varying the circumferential extent of said conducting arc which coöperates with said conducting finger for the purpose of selectively modifying the commutated wave, said means comprising a radial pivot about which at 85 least a portion of said arc may be swung out of said normal plane of revolution, a spring yieldingly holding said portion in normal position and a member attached to 90 said arc for adjusting its position.

3. A commutator for X-ray systems comprising a conducting finger adapted to revolve about a fixed axis; and a conducting arc normally concentric with said axis and coöperating with said conducting finger and fixed against revolution, said conducting arc comprising a plurality of sections one of which is radially pivoted to rotate out of its normal plane to vary the extent 100 of said conducting arc coöperating with said conducting finger.

4. In a commutator for X-ray systems, a conducting arc comprising fixed end sections and a radially pivoted central section, the 105 meeting ends of said sections normally mating closely together but permitting the rotation of said central section out of its normal plane.

5. In a commutator for X-ray systems, a 110 conducting arc comprising fixed end sections and a radially pivoted central section, the meeting ends of said sections normally mating closely together and mutually forming stops to prevent the rotation of said 115 central section in one direction but permitting its rotation in the opposite direction out of its normal plane.

6. In a commutator for X-ray systems, a 120 conducting arc comprising fixed end sections and a radially pivoted central section, the meeting ends of said sections normally mating closely together and mutually forming stops to prevent the rotation of said central section in one direction but permitting 125 its rotation in the opposite direction out of its normal plane; and spring means tending to hold said central section in normal position.

7. In a commutator for X-ray systems a 130

conducting arc at least a portion of which
is radially pivoted; a spring means tending
to rotate said portion in one direction;
means for positively rotating said portion
5 in the opposite direction; and a scale for
marking the position of said portion rela-
tively to a normal angular position.

In witness whereof, I have signed my
name to this specification, in the presence of
two subscribing witnesses.

CHARLES M. PEABODY.
